Primary Examiner—A. Hugo Word**Assistant Examiner—CathyAnne MacCormac****Attorney, Agent, or Firm—Woodard, Emhardt, Naughton, Moriarty & McNett****[57] CLAIM**

The ornamental design for a chest rest for dogs, as shown and described.

DESCRIPTION

FIG. 1 is a perspective view of a chest rest for dogs, showing my new design;

FIG. 2 is a right side elevational view thereof;

FIG. 3 is a front elevational view thereof;

FIG. 4 is a rear elevational view thereof; and,

FIG. 5 is a top plan view thereof.

The broken lines are for illustrative purposes only and form no part of the claimed design.
